UNITED STATES PATENT OFFICE.

JOHN BISHOP, OF BARTOW, FLORIDA.

FURNACE-FRONT.

No. 805,186.

Specification of Letters Patent.

Patented Nov. 21, 1905.

Application filed January 31, 1905. Serial No. 243,499.

To all whom it may concern:

Be it known that I, JOHN BISHOP, a citizen of the United States, and a resident of Bartow, in the county of Polk and State of Florida, 5 have invented a new and Improved Furnace-Front, of which the following is a full, clear, and exact description.

This invention relates to furnace-fronts; and its object is to improve the construction of 10 this part, to increase durability, and render the fire-bed more accessible.

A further object is to improve the construction of water-jacketed doors used in furnace-front construction.

Reference is to be had to the accompanying drawings, forming a part of this specification, in which similar characters of reference indicate corresponding parts in all the figures.

Figure 1 is a front elevation of the lower 20 portion of a furnace constructed according to my invention. Fig. 2 is a horizontal section taken substantially upon the line 2 2 of Fig. 1. Fig. 3 is also a horizontal section taken substantially upon the line 3 3 of Fig. 1. This 25 section passes through the fire-door, as will appear. Fig. 4 is a vertical section taken substantially upon the line 4 4 of Fig. 1. Fig. 5 is a horizontal section through the furnace-front shown in Fig. 6 and passing through 30 the fire-doors, and Fig. 6 is a front elevation showing the construction as applied to wide furnaces with double doors.

Referring more particularly to the parts, 1 represents the forward wall of a furnace, which 35 furnace may be of any common construction. Just to the rear of the forward wall 1 a hearth 2 is provided, which supports the forward extremities of longitudinally-disposed grate-bars 3. As indicated most clearly in Fig. 3, 40 the wall 1 is provided, preferably centrally, with an opening that is to be closed by a door 4, the construction of which will be described more fully hereinafter. The fire-door 4 is arranged near the inner portion of the wall, so 45 that the inner face 5 of the wall is substantially flush with the inner face of the fire-door. Furthermore, the inner face 5 referred to is curved, as shown in Fig. 3, on either side of the doorway, so as to form a horizontal 50 arch having its crown at the doorway, the base of the arch intersecting the side walls 6 of the furnace at an obtuse angle, as shown. At the aforesaid doorway the forward wall is formed with forwardly-diverging cheeks 7, as 55 shown. Substantially the entire area of the wall 1 is covered by a face-plate 8, the body

of which is secured in position by means of suitable bolts 9 or similar devices. This face-plate 8 conforms substantially to the configuration of the wall, as illustrated in Fig. 3, presenting inclined side plates or jambs 10, which lie against the aforesaid cheeks 7. The inner edges 11 of these side plates lie adjacent to the inner face 5 of the forward wall and are preferably beveled, as shown, so that they are 60 substantially protected from exposure to the heat of the fire. This construction of the doorway and forward wall of the furnace renders the fire-bed very accessible and facilitates the operation of slice-bars and other fire-tools. 65 By reason of the widely-diverging doorway the spaces at the sides and at the front of the fire-bed become readily accessible. The horizontal-arch construction constitutes a substantial reinforcement for the front of the furnace, tending to resist wear and tear due to 70 the slamming of the furnace-door.

The fact that the furnace-wall does not project inwardly beyond the doorway is advantageous, as in operating the fire-tools they are 80 likely to strike against the edges of the projecting parts, so as to dislodge the fire-brick lining.

The face-plate 8 also has an upper transverse member or lintel 12, and the body of 85 this lintel, as indicated in Fig. 4, is inclined and preferably is provided with a horizontal lower extension 13. As indicated, the brick-work of the opening substantially conforms at this part to the peculiar formation of the 90 face-plate. This lintel operates to support the brickwork 14 above the same, as will be readily understood.

Beneath the fire-door 4 the side plates 10 are connected by face-strips 15 16, the same 95 being separated, as shown, in order to receive an ash-door 17 therebetween. The fire-door 4 consists of a hollow plate presenting a water-chamber 18, as shown. The edge of the plate above this water-chamber is provided with 100 perforations 19 for the purpose of enabling evaporation to the outer air. The door at a suitable point is provided with a handle 20, which consists of a vertically-disposed pipe having a flaring upper mouth 21, the said 105 handle being closed at its lower extremity. This tubular handle is in communication with the water-chamber 18 through hollow thimbles or pipe connections 22.

In order to supply the water-chamber 18 110 and the interior of the handle 20 with water, I provide a water-pipe 23, which passes into

the front wall of the furnace, preferably from the side, as shown. This pipe passes through the lower portion of the brickwork 14 and terminates at 24, which is the point vertically 5 above the open mouth 21, as shown in Fig. 4. A valve 25 controls the water-supply through this pipe and would be normally regulated, so that a small quantity of water would constantly drip down into the tubular handle, replenishing the loss of water due to evaporation. In practice the amount of water supplied in this manner should be slightly in excess of that evaporated. The water not evaporated would then overflow at the upper edge 10 of the mouth 21 and pass downwardly upon the outer surface of the handle, helping to keep the same cool, as will be readily understood. At the lower portion of the fire-door 4 a drain-cock 26 is arranged as indicated. The 15 door may be mounted in any suitable manner, such as by hinges 27, as shown, and a catch 28 will be provided for maintaining the door in a closed position.

As shown most clearly in Fig. 3, the side 20 edges of the door are beveled, so as to conform to the direction of the side plates 10, lying snugly against their outer faces, as will be readily understood.

The lintel 12 constitutes a support for the 25 bricks above the doorway and dispenses with the necessity for an arch over the doorway. At the same time the lintel is protected on account of its position from the heat of the fire, and this prevents any tendencies for it 30 to collapse under the continued effect of the weight and heat. For this reason the invention is especially useful in connection with the wide doorways which are so favorably regarded by furnacemen. Normally these 35 doors necessitate a wide span for the arch, and this disadvantage operates against their more general use.

A furnace-front constructed substantially as described possesses many other advantages 40 over the furnace-fronts of ordinary construction. These advantages relate especially to the horizontal-arch construction referred to above, which facilitates the care of the fire. The fact that the fire-door 4 is water-jacketed 45 is also highly advantageous, as it prevents the door from becoming highly heated and warping out of shape.

In Fig. 5 a wide furnace-front is illustrated, the wall being provided with an opening 27^a, closed by double doors 28^a, hinged at 29 to the 50 jambs 30. These doors have water-jackets 31, which would be independently supplied with water through tubular handles 32 in communication with the water-chambers, as before described. The lintel 33 affords ample support for the brickwork 34 thereabove in the manner before described.

The manner described for feeding the water to the doors is considered especially desirable. In the methods heretofore employed 55 the feed connections have usually been made at the hinge-joints and were leaky and likely to get out of order. With my arrangement these defects are readily overcome.

While the furnace-front described is a construction especially adapted for use in connection with a drier-furnace, evidently the invention may be used in connection with furnaces for boilers or for other purposes.

Having thus described my invention, I claim 75 as new and desire to secure by Letters Patent—

1. A water-jacketed fire-door having a hollow handle in communication with the water-space within said fire-door.

2. A fire-door for a furnace presenting a 80 water-chamber, a hollow handle in communication with said chamber and presenting an opening adapted to receive water to replenish the supply within said chamber, and means for allowing water to drip through said opening. 85

3. A fire-door for a furnace having a water-chamber, a substantially vertical tubular handle attached to the outer face of said door, and presenting an opening, tubular thimbles connecting said handle with the water-chamber 90 of said door, and means for supplying water to said opening.

4. A furnace-front having a lintel supporting the brickwork thereabove, said lintel presenting a lower face exposed to the atmosphere, and a fire-door at the inner edge of 95 said lintel, and protecting the same from the fire-heat.

5. A furnace-front having a wall with an opening therethrough, a lintel supporting said 100 wall above said opening, and a door substantially flush with the inner edge of said lintel and protecting the same from the fire-heat.

6. A furnace-front having a wall with an opening therethrough, a lintel supporting the 105 said wall above said opening, said wall projecting over the inner edge of said lintel to screen the same, and a fire-door substantially flush with the inner edge of said lintel, said fire-door affording means for screening the 110 under side of said lintel from the fire-heat.

7. A furnace-front having a wall built of blocks such as bricks, laid in the form of a curve disposed in a substantially horizontal plane and widening toward the side walls of 115 the furnace.

In testimony whereof I have signed my name to this specification in the presence of two subscribing witnesses.

JOHN BISHOP.
